UNITED STATES PATENT OFFICE.

JOHANN FEY, OF ITZEHOE, GERMANY.

LOCK.

SPECIFICATION forming part of Letters Patent No. 451,709, dated May 5, 1891.

Application filed October 9, 1890. Serial No. 367,610. (No model.) Patented in Germany February 1, 1889, No. 48,765.

To all whom it may concern:

Be it known that I, JOHANN FEY, a subject of the King of Prussia, and residing at Itzehoe, Kingdom of Prussia, in the German Empire, have invented new and useful Improvements 5 in Door-Locks, (for which I have obtained Letters Patent No. 48,765 in the German Empire on the 1st day of February, 1889,) of which the following is a specification.

10 The object of my invention is to provide a door-lock which is so constructed that the latch-bolts can be locked in place when in outward position, thus preventing the door from being opened by turning the usual knob-spindle.

15 The invention consists in the construction and combination of parts and details, which will be fully described hereinafter, and finally pointed out in the claims.

20 In the accompanying drawings, Figure I is a representation of my improved lock, the face-plate being removed and the parts being in the position that they have when the latch-bolts are locked in place. Fig. II is a similar 25 view showing the positions of the parts when the latch-bolts are unlocked, thus adapting the door to be opened; and Fig. III is a vertical transverse sectional view on the line $x-x$, Fig. 2.

30 Similar letters of reference indicate corresponding parts.

The two latch-bolts A and B, which are in general of the usual construction, are each provided with an extension f , provided with 35 a longitudinal slot f' , into which a lug e projects from the plate C, the outer ends of said latch-bolts passing through apertures in the end plates D. A spiral spring d is secured to each latch-bolt and to the casing and 40 serves for the purpose of pulling the latch-bolts outward. The spindle-rose a is provided with a square aperture a' , through which the spindle can be passed. The rose is provided with an upwardly-projecting arm b , having a rounded head which enters a notch in the bottom of the upper latch-bolt A. The said rose is also provided with a downwardly-projecting arm b' , adapted to act on the upper arm c' of a lever $c' c^2$, pivoted to 45 the plate C, the lower end of the arm c^2 and of the lever $c' c^2$ being provided with a rounded head that passes into a notch in the

upper edge of the latch-bolt B. The latch is provided with two locking-bolts E and F, adapted to slide on the plate C at right angles 55 to the latch-bolts A and B in such a manner that the inner ends of said latch-bolts A and B can abut against said lock-bolts E and F. The upper lock-bolt E is provided with a recess q , extending upward from the bottom 60 edge of the same. In one edge of each recess a series of notches r are formed for receiving projections s on the inner face of a tumbler G, mounted to swing on a pin p , that passes through the recess q of the sliding lock-bolt 65 E. A spring t is connected with the tumbler G and presses the same in the direction toward the key-hole g' , in which the key g can be inserted. The upper locking-bolt E is provided with a notch h , into which the bit of 70 the key can pass, part of which notch h is overlapped by the tumbler G. The bottom locking-bolt F is provided with a longitudinal slot n , into which a lug o projects from the plate C for the purpose of guiding said bot- 75 tom bolt. A lever $i' i^2$ is pivoted at i on the plate C, and is provided at its ends with longitudinal slots $l' l^2$, into which pins project from the lower end of the locking-bolt c and the upper end of the part m of the locking-bolt F. 80

The operation is as follows: When the parts are in the position shown in Fig. 2 and the spindle is turned, the latch-bolts A B are withdrawn and the parts brought into the position shown in dotted lines in Fig. 2. The 85 door can now be opened and closed in the ordinary manner by turning the knob-spindle. When it is desired to lock the parts, the key is inserted and turned, whereupon the bit of the key, acting on the edge of the tumbler 90 G, presses said tumbler in the direction from the key-hole in such a manner as to disengage the projection s on the tumbler from the notches r on the locking-bolt E, thus permitting the bit of the key which acts on one edge 95 of the notch h to press said lock-bolt E upward and bring it in such a manner that its side edge abuts against the inner end of the upper latch-bolt A. By means of the lever $i' i^2$ the lower locking-bolt F is moved down- 100 ward and in such position that its side edge abuts against the end of the bottom latch-bolt B, thus locking both latch-bolts in place and preventing their being withdrawn by the

turning of the knob-spindle. Whenever it is desired to unlock the latch-bolts it is only necessary to turn the key in the reverse direction, whereby the locking-bolts E and F are moved toward each other and clear the inner ends of the latch-bolts.

This improved lock is adapted for house-doors, closet-doors, or other similar purposes.

Having thus described my invention, I claim as new and desire to secure by Letters Patent—

1. In a door-lock, the combination, with two latch-bolts, of two lock-bolts for locking said latch-bolts, and a tumbler engaging one of said lock-bolts, substantially as set forth.
- 15 2. In a door-lock, the combination, with a

casing, of two latch-bolts and two locking-bolts adapted to slide at right angles with the latch-bolts and to engage the same, one of the lock-bolts having notches, an additional tumbler also having notches and adapted to engage the notched lock-bolt, which notched lock-bolt also has a recess for the key-bit, and a pivoted lever, the opposite ends of which are connected with the two lock-bolts, substantially as set forth.

In witness whereof I have hereunto set my hand in presence of two witnesses.

JOHANN FEY.
